PORTABLE HEAD REST

Calvin T. Kinsman, South Miami, Fla.
(700 Sunset Blvd., New Port Richey, Fla.)
Filed Feb. 1, 1961, Ser. No. 86,448
3 Claims. (Cl. 297—397)

This invention relates to portable head rests. One example of the use of such head rests is as a removable structure for support upon the back of a vehicle seat for augmenting the height of the back so that the back of the head of an occupant of the seat may rest against the structure.

The structure of this invention is an improvement upon those disclosed in my copending application Serial No. 847,350 for Portable Head Rests, filed October 19, 1959, which has matured in Patent No. 2,996,333 dated August 15, 1961, particularly in that the new structure is so constructed that it will not be apt to creep upwardly nor accidentally move sidewise but will positively move with movements of the torso of an occupant of a vehicle seat who is using the head rest. That is, as the occupant's body may move along a vehicle seat, the head rest will follow the movements of the body and the body will not slide off the head rest.

Since one of the important objects of my prior invention, referred to above, was to provide a head rest constructed of inexpensive material, readily fashioned, and light in weight, an improvement thereover is the provision of a head rest wherein there is a saving in material over that employed in the head rests of my prior invention, without the sacrifice of the novel features of the prior invention. With this saving, and employing the same materials as heretofore, the cost of manufacture is lowered and the weight of the finished head rest is reduced.

Additionally, an important object of the present invention is to provide a head rest which does not include the slight bulge, extending from the front of one of the forms of my prior invention. While, in many cases, this bulge was not objectionable, in a few cases it might be regarded as such.

Still another important object of the invention is to provide an adjustable bridge means between front and back portions of the head rest, which bridge means will not move forwardly beyond the front face of the front portion of the head rest.

Still another important object is to provide a portable head rest which may be shipped, stored and marketed as a flattened-out article or may be shipped, stored and especially marketed as a compactly folded article, whereby the compactly folded article is of much less size than is the same article flattened out.

Other objects and advantages of the invention will be apparent during the course of the following detailed description of the invention, taken in connection with the accompanying drawing, forming a portion of the disclosure, and in which drawing:

FIGURE 1 is a perspective view of the portable head rest of this invention as in use.

FIGURE 2 is a knocked-down or collapsed view of the head rest of FIGURE 1.

FIGURE 3 is a virtual longitudinal section through the head rest of FIGURES 1 and 2 in use.

FIGURE 4 is a horizontal transverse sectional view substantially on the line 4—4 of FIGURE 3.

FIGURE 5 is a sectional view through the folded-up head rest, the section being on substantially the longitudinal medial line of the head rest.

In the drawing, wherein for the purpose of illustration is shown a preferred embodiment of the invention and wherein similar reference characters designate corresponding parts throughout the several views, the letter A

2

designates the embodiment of the invention; B, the back of a seat; C, an occupant of the seat; and D, garment worn by the occupant.

The portable seat back A preferably comprises a single sheet of self-sustaining, readily stamped or die cut material which may be scored and bent or folded. Such material may be fibrous material as cardboard, the laminated corrugated paper board commonly known as "jute or jute board" and similar self-sustaining stiffened fibrous materials. By way of example, I have discovered that a substantially rectangular sheet of jute board, substantially twenty-eight inches long, substantially eight inches wide, about one-eighth inch thick, and weighing substantially five and one-half ounces is a practical size and weight. This size sheet is substantially seven and one-half inches shorter than a practical embodiment of the sheet of the head rest A of my disclosure in application Serial No. 843,350, referred to above, since there is no wastage of material in the present form of the invention in providing a tongue portion which forms bridge means in the present form, as will be more fully described later.

The sheet 10 preferably has substantially parallel side edges 11 and opposite end edges 12 and 13 and a plurality of substantially parallel tongue-receiving transverse slots, as the slots 14, 15 and 16, spaced inwardly from the side edge 12, extending toward the opposite end edge 13. The slots are narrow, such as one-eighth inch wide and very slightly more than two-and-one-quarter inches long, leaving substantially two-and-three-quarter inches of material outwardly of the preferably square-cut end edges of the slots. While three slots are shown, by way of example, there may be two, four or more slots, instead of three.

Spaced from the slots 14—16 and end edge 13 are 35 spaced-apart, transversely-extending score or fold lines 17 and 18. Preferably, these extend, in arcuate curves, toward each other so that they are spaced apart their least distance at substantially the longitudinal medial line of the sheet. For example, at the edges 11 the two lines 17 and 18 may be substantially one-and-one-quarter inches apart and substantially one-eighth inch at the longitudinal medial line. For example, the line 18, at the edges 11, may be about nine inches from the end edge 12 and about eighteen-and-one-half inches from the end edge 13. The edge 12 and line 17 define the longitudinal limits of rear portion 19 of the set-up head rest A and the line 18 and end edge 13 define the longitudinal limits of the front portion 20 of the set-up head rest, which front portion comprises a lowermost or back-contacting part 20^a and an upper or head-contacting part 20^b.

Extending longitudinally of the body-contacting part 20^a of the front portion 20 are a pair of substantially parallel cuts 21 and, joining them, preferably adjacent the edge 13, is a transverse cut 22. The shortest distance apart of the cuts 21 is very slightly less than the length of any one of the slots 14—16, since the tongue 23 provided by the material between the lines 21, inwardly of the line 22 and inwardly of a hinge line 24 which, when the tongue 23 is folded away from the front portion 20, as will be described, is very slightly narrower than any one of these slots but wide enough so that there will be a snug friction hold of the tongue in the slots. Of course, the length of the tongue 23 may vary, but I prefer to provide one about nine inches long which will accommodate the head rest A to seat backs of various thicknesses. It is important that there be adequate material of the front portion 20 between adjacent lines 11 and 21 and 12 and 21. For example, the shortest distance between these associated lines should be substantially three and three-eighth inches while the

tongue 23 is substantially two and one-quarter inches wide.

In order to assist in folding up the head rest A into a compact article, much shorter than the flattened out article, I provide a fold or score line 28 preferably extending across the part 20^a, for example, in substantially the location shown in FIG. 2 so that the part below the fold or score line 28 may be folded toward the line 18, as may be appreciated in FIG. 5. The tongue 23 may also be provided with a fold or score line 29 so that, when the tongue is folded toward the line 18, that portion of the tongue below the line 29 of FIG. 2 may also be folded, as is believed clear in FIG. 5. Thus, as shown in FIG. 5, a compact package is provided.

The juncture of the edges 11 and 12 with the edge 13 may be rounded, if desired and the edge 12 slightly curved.

The head rest A is preferably handled in its flattened-out or collapsed shape which permits stacking without any lost space.

In setting up the head rest A, the sheet 10 is folded along the score lines 17 and 18 to provide a somewhat inverted V-shape, the tongue 23 then bent on the scored fold line 24 and inserted in the slot 14. The head rest is then mounted upon the top surface 30 of the back B with the portion 20 facing forwardly and the lower part of the back portion 19 facing rearwardly. The operation may now pinch the portions 19 and 20 toward each other at the apex at the upper end of the head rest, by the use of the fingers of one hand, so that the front and rear portions will contact the front face 31 and back face 32 respectively of the seat back B and, with his other hand, bend up at 25 that portion of the tongue 23 protruding outwardly of the slot 14 and fold the protruding portion of the tongue at 26 so that the free end portion 27 may be inserted through the slot 15 or 16 (in the example shown in FIG. 1, the free end portion 27 is inserted through the slot 16, but, if the portion of the tongue 23 contacting the top surface of a seat back is thinner than that shown in FIG. 1, the free end may be inserted through the slot 15). Taken with the snug fit of the tongue with the walls of the slots and the folds 25 and 26 and protruding free end portion 27 of the tongue, the tongue is securely held against accidental separation from the back portion 19.

Of course, without invention, I may provide a plurality of transversely score or fold lines 29^a, similar to the line 29 at the lower end portion of the tongue 23 for assisting in folding the free end portion of the tongue while being manipulated into the slots, such as the slots 14, 15 or 16.

Preferably, the occupant C, when sitting into the seat places the hand 40 (or even the other hand) upon the head rest A, as shown in FIG. 1, at the part thereof between the two fold lines 17 and 18 and presses slightly downwardly in the event the portion of the tongue 23, which provides, in effect, a bridge means between the rear and front portions 19 and 20, accidentally moves upwardly. The occupant may then lean against the front portion of the head rest and release the hand 40 from the head rest. The elongate opening or slot 28 which is provided by the walls of the cuts 21 and 22 and fold lines 24 is adapted to receive, as may be appreciated in FIGS. 3 and 4, a portion 45 of the garment D of the occupant C, a part of which portion 45 may or may not contact the generally smooth surface of the front face of the seat back, fills the slot 28 and thus tends to prevent undesired independent movements of the head rest A over the seat back but which head rest may move with movements of the occupant's body, whereby the occupant will not find it necessary to readjust the head rest with relation to the occupant's body. Head rests without this feature sometimes tend to "freeze" to the seat back and, if the user attempts to move to the right

or left, the occupant's body tends to slide off the back rest and then to be whipped, by breezes, from the seat back.

If desired, a coating of conventional water-repellent composition may be applied to the outer face of the front portion 20.

Various changes in the shape, size, and arrangement of parts may be made to the form of the improved invention without departing from the spirit of the invention or scope of the claims.

What is claimed is:

1. A portable head rest of self-sustaining sheet material for a seat back having a front face, a rear face and a top edge, said portable head rest including a back portion for contacting a portion of said rear face, a front portion having a back-contacting part for contacting said seat back and a portion of the back of a garment worn by an occupant of such seat back and leaning against said portable head rest, said front portion also having a head-contacting part merging into said back-contacting part and said back-contacting part being provided with an elongate longitudinally extending opening extending from the front face to the rear face of said back-contacting part; and manually foldable bridge means connecting said front portion, intermediate the height thereof, and said rear portion, with a portion of said bridge means forming substantially a right angle with said head-contacting portion, said opening being of an area sufficient to accommodate a part of said back portion of said garment to project into said opening, whereby sidewise movements of the torso of the occupant will tend to cause said part of said garment to move sidewise with said torso and cause said head rest to move therewith.

2. A portable head rest of self-sustaining sheet material for a seat back having a front face, a rear face and a top edge, said portable head rest including a back portion for contacting a portion of said rear face, a front portion longer than said back portion and having a back-contacting part for contacting said seat back and a portion of the back of a garment worn by an occupant of such seat back and leaning against said portable head rest, said front portion also having a head-contacting part merging into said back-contacting part and said back-contacting part being provided with an elongate longitudinally extending slot extending from the front face to the rear face of said back-contacting part; and manually foldable bridge means connecting said front portion, at the base of said slot, and said rear portion closely adjacent the lower end of said rear portion, with a portion of said bridge means forming substantially a right angle with said head-contacting portion, said slot being of an area sufficient to accommodate a part of said back portion of said garment to project into said opening, whereby sidewise movements of the torso of the occupant will tend to cause said part of said garment to move sidewise with said torso and cause said head rest to move therewith.

3. A portable head rest of self-sustaining sheet material for a seat back having a front face, a rear face and a top edge, said portable head rest including a rear portion for contacting a portion of said rear face, a front portion having a back-contacting part for contacting said seat back and a portion of the back of a garment worn by an occupant of such seat back and leaning against said portable head rest, said front portion also having a head-contacting part merging into said back-contacting part and said back-contacting part being provided with an elongate longitudinally-extending opening extending along the longitudinal axis of said back-contacting part and extending from the front face to the rear face of said back-contacting part; and manually foldable bridge means connecting said front portion, at a fold line at the base of said slot, and said rear portion, with a portion of said bridge means forming substantially a right angle

with said head-contacting portion, said opening being of an area sufficient to accommodate a part of said back portion of said garment to project into said opening, whereby sidewise movements of the torso of the occupant will cause said part of said garment to move sidewise with said torso and cause said head rest to move therewith.
